Primary Examiner — Marie D. Fast Horse

(57) **CLAIM**

The ornamental design for a communication device body as shown and described.

DESCRIPTION

FIG. 1 is a top, front and right side perspective view of a communication device body showing our new design; FIG. 2 is a bottom, rear, and left side perspective view of the communication device body; FIG. 3 is a front view of the communication device body; FIG. 4 is a right side elevation view of the communication device body;

FIG. 5 is a rear elevation view of the communication device body;

FIG. 6 is a left side elevation view of the communication device body;

FIG. 7 is a top plan view of the communication device body; and,

FIG. 8 is a bottom plan view of the communication device body.

The broken lines shown in the drawings depict portions of the communication device body that form no part of the claimed design.

1 Claim, 5 Drawing Sheets
